E. A. HOLMGREN

MACHINE FOR SHAPING UPPERS OVER LASTS

Filed Oct. 22, 1919

Patented May 1, 1923.

1,453,274

UNITED STATES PATENT OFFICE.

ERIC A. HOLMGREN, OF LYNN, MASSACHUSETTS, ASSIGNOR TO UNITED SHOE MACHINERY CORPORATION, OF PATERSON, NEW JERSEY, A CORPORATION OF NEW JERSEY.

MACHINE FOR SHAPING UPPERS OVER LASTS.

Application filed October 22, 1919. Serial No. 332,520.

To all whom it may concern:

Be it known that I, ERIC A. HOLMGREN, a citizen of the United States, residing at Lynn, in the county of Essex and State of Massachusetts, have invented certain Improvements in Machines for Shaping Uppers Over Lasts, of which the following description, in connection with the accompanying drawings, is a specification, like reference characters on the drawings indicating like parts in the several figures.

This invention relates to machines for shaping uppers over lasts, and is herein shown as applied to a machine having means for pulling an upper over its last and means for overlaying and fastening the margin of the upper. The invention is herein illustrated by reference to characteristic features of a well known type of pulling-over machine the general organization of which is shown and described in United States Letters Patent No. 1,029,387, granted on June 11, 1912, upon an application of R. F. McFeely, but it will be understood that the invention is not limited in its application to machines of this particular type.

An object of the invention is to insure that the fastenings whereby the upper is held shall be located in proper relation to the edge of the shoe bottom, and to this end a feature of the invention consists in a novel construction and arrangement of mechanism for controlling the fastening means. The invention is herein shown as applied to a type of construction comprising overlaying and fastening means arranged to be moved inwardly toward the shoe against the resistance of the tensioned upper by mechanism parts of which are relatively movable in response to resistance encountered by such means in its inward movement to actuate the fastener driving means, and in accordance with the illustrative embodiment of the invention means is provided for positively preventing such relative movement of the parts until the fastening means has arrived in a predetermined relation to the shoe. More specifically, the construction shown comprises a toggle connection arranged to be maintained in a substantially straightened condition for imparting inward movement positively to the overlaying and fastening means and mechanism for breaking the toggle when said means has

arrived substantially in position for driving the fastenings. Further objects are to provide a construction requiring comparatively little power for its operation and avoiding objectionable strains on the operating parts, and additional features of the invention are to be recognized in the novel construction whereby these objects are attained.

In a further aspect, a feature of the invention is to be recognized in the provision of means controlled by the shoe for insuring a predetermined relation between the shoe and the overlaying and fastening means, the construction shown comprising members positioned in accordance with the width of the shoe for interrupting the positive connections between the side overlaying and tacking devices and their operating means only when said devices have been moved to positions determined by the shoe. Still another feature consists in the provision of supplemental means for assisting in preventing outward return movement of overlaying and fastening means in the upper fastening operation.

These and other features of the invention, including certain details of construction and combinations of parts, will now be described with reference to the accompanying drawings and pointed out in the claims.

In the drawings:

Fig. 1 is a view substantially in front elevation, with parts shown in section, of a portion of a pulling-over machine in which the invention is incorporated;

Fig. 2 is a view of a portion of the mechanism of Fig. 1, showing the parts as positioned at an earlier time in the cycle of operations; and

Fig. 3 is a view substantially in plan, with parts in section, showing a portion of the mechanism for operating the overlaying and fastening devices shown in Fig. 1.

Machines of the illustrative type, as fully shown and described in said prior McFeely patent, comprise in their organization grippers for engaging the upper at the end and at opposite sides of the last, the present drawing showing the side grippers only which are connected to updraw levers 2 and are operated to pull the upper against the resistance of a sole rest 4 in engagement with which the shoe is initially positioned. The several grippers are operated to pull

the upper over the last and then hold the upper under tension with the machine at rest to permit inspection and adjustment of the work. Following a subsequent starting 5 of the machine, shoe clamping and supporting devices 6 are swung inwardly against the shoe at its opposite sides and either immediately or following a second period of rest in the cycle of operations, overlaying 10 and fastening devices are moved inwardly at the toe end and at the opposite sides, the grippers being tripped by the inward movement of these devices to cause them to release the upper and the tacks or equivalent 15 fastenings being finally driven to secure the margin of the upper in place.

Only the devices for overlaying and fastening the upper at the sides are shown in the accompanying drawings, these devices 20 comprising side arms 8 which are mounted to swing laterally of the shoe about supporting bearings 10. Mounted on the lower ends of the arms 8 are overlaying wiper plates 12 which are supported under tack 25 carrying blocks 14 in such manner as to permit them to tip upwardly and downwardly and also to yield backwardly against the resistance of the shoe materials. The outer ends of these plates are curved upwardly 30 over rolls 16 which are mounted on spring plungers 18 and are pressed upwardly against the curved outer ends of the plates to hold the plates with their upturned inner ends normally in a downwardly inclined and 35 advanced position. The wiper plates are thus arranged to engage the shoe below the edge of the sole or insole while the upper is still held by the grippers and, as the arms 8 are advanced, to wipe the upper with 40 firm pressure over the edge of the insole and inwardly from the edge. During this operation the wiper plates may yield upwardly and backwardly under the control of the spring plungers 18, as shown in Fig. 2. In 45 the continued movement of the arms, the grippers are tripped to cause them to release the upper, whereupon the decreased resistance permits the spring plungers 18 to react and to wedge the wipers farther inwardly while forcing their inner ends downwardly against the shoe with substantial 50 pressure. With the parts thus positioned the tacks are driven to fasten the margin of the upper in place.

55 The tacks may be fed to the tack blocks 14 in a well-known manner, as illustrated in said prior patent, and as thus positioned in the blocks are operated upon by drivers 20 which are mounted on driver bars 22 60 slidably supported on the arms 8 and connected at their upper ends to spring operated driver arms 24. The driver bars 22 are provided with shoulders 26 (Fig. 3) which are engaged by the edges 28 of slides 65 30 to uphold or lock the driver bars nor-

mally against the pressure of the arms 24. The slides 30 are mounted on a bracket plate 32 which is pivotally supported on a shaft 34, and are connected by means of gear segments 36 to a slide bar 38 whereby movement is imparted at a definite time in the cycle to the slides 30 to withdraw their edges 28 from under the shoulders 26 and permit the driver bars to be operated to drive the tacks. Subsequently, in the return 70 of the parts to starting position, the bracket plate 32 is swung downwardly and then upwardly, the slides 30 being in the meantime returned to their outer positions to cause them to engage under the shoulders 26 and 75 to lift the driver bars in preparation for the operation of the machine upon another shoe. For more detailed information with respect to the construction and mode of operation of the parts as thus far described, reference 80 may be made to said prior McFeely patent.

As in prior constructions, the slide 38 and its connected mechanism are further utilized as means for swinging the toe and side arms inwardly to overlay the margin of the upper and to position the tackers in operative relation to the shoe. For the purpose of thus operating the side arms 8 shown in the drawings, the present invention provides novel mechanism connecting the slides 30 to the lower end portions of the arms. Pivotally mounted to swing about the same axes as the arms 8 are operating arms 40 provided between their opposite ends with lateral extensions 42 carrying balls 44 engaging in guideways 46 formed on the outer ends of the slides 30, these guideways being curved about the axis of movement of the plate 32 to permit the plate to swing as hereinbefore described without interrupting its connection with the arms 40. At their lower ends the arms 40 are connected to the side arms 8 by toggle mechanisms each comprising a lever 48 pivoted on the arm 40 and connected at its inner end to a lever or link 50 which is pivoted at 52 on the arm 8. A spring 54 connected to the outer end of the lever 48 tends to hold it against a stop pin 56, in which position it is substantially in line with the link 50 and co-operates with the link to provide a rigid connection between the arm 40 and the arm 8. Through these connections movement is imparted positively to the arms 8 by the inward movement of the slides 30 to operate the wipers and to carry the tackers into proper relation to the edge of the shoe bottom.

Depending from the pivot pin 52 is a finger 58 which is arranged to bear on the end of an adjustable screw 60 carried by a depending lug on the link 50, and in the inward movement of the arm 8 engages an abutment member 62 on the underlying clamping device, as shown in Fig. 2, the position of the member 62 being determined 120 125 130

by the shoe as the clamping device adjusts itself in accordance with the width of the shoe. The screw 60 is preferably so adjusted that the finger 58 engages the member 52 substantially at the time when the grippers are tripped to release the upper and permit the wiper plates to be forced farther inwardly by reason of the decreased resistance, the finger being operated by the continued 10 movements of the arms 8 and 40 to break the toggle 48, 50 and interrupt the positive connection between the two arms. To facilitate the breaking of the toggle a pin and slot connection is provided between the adjacent 15 ends of the members 48 and 50. The arm 40 then becomes operative through a spring 64, which is guided by a rod 66 fast on the arm 8 and extending loosely through a slot in the arm 40, to apply yielding pressure to the 20 arm 8, whereby a slight further movement of the arm 8 to position the tacking mechanism relatively to the shoe may be effected against the decreased resistance. As the arm 8 arrives at its limit of inward movement 25 determined by engagement with a shoulder 68 on the underlying clamping device, continued movement of the arm 40 serves to compress the spring 64 to hold the tacking mechanism securely in operative position, such movement of the arm being accompanied by movement of the slide 30 relatively to the now stationary arm 8, as hereinbefore explained, to withdraw its edge 28 from under the shoulder 26 on the driver bar 32 and thus release the driver bar and cause 35 the tack or tacks to be driven.

From the above description it will be evident that the greater portion of the inward movement of each of the arms 8 and its supported overlaying and fastening devices, during the time that the greatest resistance is encountered in wiping the upper over the edge of the sole and in pressing the wipers inwardly against the margin of the upper 40 while the latter is still held by the grippers, is effected through a positive connection, and that it is only when the resistance is substantially decreased by the tripping of the grippers that the positive connection is 45 interrupted by the breaking of the toggle. After the toggle is broken the spring 64 serves as a sufficiently effective connection between the two arms to cause the inward movement of the arm 8 against the decreased 50 resistance to be completed prior to such an extent of relative movement between the arms 8 and 40 as to cause the edge 28 of the slide 30 to be withdrawn from under the shoulder 26 on the driver bar. As soon as 55 the inward movement of the arm 8 is stopped by engagement with the abutment shoulder 68, the continued movement of the slide 30 serves to release the driver bar and cause the tacks to be driven, the tacking devices now 60 being positioned and held by the spring 64 in the relation to the edge of the shoe bottom determined by the abutment 68. It will be evident that this construction not only contributes to effectiveness in the action of the wiper plates, but also affords insurance 70 against driving the tacks in an incorrect location as has sometimes happened in the use of prior constructions on heavy shoes by reason of resistance of the shoe materials sufficient to overcome the tension of the 75 yielding portion of the operating connections and cause premature release of the driver bars. In the construction herein shown the overlaying and fastening means is moved inwardly by positively operating 80 mechanism which is under control of the shoe through the abutments 62 on the side clamps to insure a predetermined relation between said means and the shoe before the fastenings can be driven. It will also be 85 evident that the arrangement whereby the operating means for the arm 8 is connected to the arm at its lower end adjacent to the overlaying and tacking devices is effective 90 as guarding against such strain on the arm as might cause the driver bar to bind on its bearing and also permits the inward movement of the arm to be effected by the use of less power than required where the operating connections are positioned approximately 95 midway of the length of the arm as in prior constructions.

While the invention is herein shown as embodied in mechanism designed to operate at the sides of the shoe, it will be understood 100 that the invention is not thus limited but is applicable also to the means whereby similar operations are performed at the toe end of the shoe.

Features of the upper gripping mechanism 105 herein shown are not claimed in this application but in a divisional application, Serial No. 544,915, filed March 18, 1922.

Having described the invention, what I claim as new and desire to secure by Letters 110. Patent of the United States is:

1. In a machine of the class described, the combination with means for pulling an upper over a last, of overlaying and fastening means, and mechanism for moving said overlaying and fastening means toward the shoe including parts arranged for relative movement in response to resistance encountered by said means in its movement toward the shoe to actuate the fastening means and a 115 positively operating device for preventing the relative movement of said parts until the fastening means has arrived in a predetermined relation to the shoe.
2. In a machine of the class described, the 120 combination with means for pulling an upper over a last, of overlaying and fastening means, mechanism for moving said overlaying and fastening means toward the shoe including parts arranged for relative move- 125

130

- ment in response to resistance encountered by said means in its movement toward the shoe to actuate the fastening means and a device for normally preventing the relative movement of said parts, and means arranged to act on said device at a definite point in the movement of said overlaying and fastening means toward the shoe to cause the actuation of the fastening means.
3. In a machine of the class described, the combination with means for pulling an upper over a last, of overlaying and fastening means, mechanism for moving said overlaying and fastening means toward the shoe including parts arranged for relative movement in response to resistance encountered by said means in its movement toward the shoe to actuate the fastening means and a toggle arranged to be held substantially straight to prevent the relative movement of said parts, and means operative at a definite point in the movement of said overlaying and fastening means toward the shoe to break said toggle and cause the actuation of the fastening means.
4. In a machine of the class described, the combination with means for pulling an upper over a last, of overlaying and fastening means, mechanism for moving said overlaying and fastening means toward the shoe including parts arranged for relative movement in response to resistance encountered by said means in its movement toward the shoe to actuate the fastening means and a device for normally preventing the relative movement of said parts, and means including a stop into operative relation to which said device is carried by the movement of said overlaying and fastening means toward the shoe for operating said device to cause it to release said parts for relative movement.
5. In a machine of the class described, the combination with means for pulling an upper over a last, of overlaying and fastening means, mechanism for moving said overlaying and fastening means toward the shoe including parts arranged for relative movement in response to resistance encountered by said means in its movement toward the shoe to actuate the fastening means and a toggle arranged to be held substantially straight for normally preventing the relative movement of said parts, and toggle operating means including a stop arranged to become operative at a definite point in the movement of said overlaying and fastening means toward the shoe to break the toggle and cause the actuation of the fastening means.
6. In a machine of the class described, the combination with means for pulling an upper over a last, of overlaying and fastening means including a driver bar, mechanism for moving said overlaying and fastening means toward the shoe comprising a member ar-
- ranged to hold said driver bar normally against driving movement and a device for preventing relative movement between said member and the driver bar to release said bar, and means for operating said device at a predetermined point in the movement of said overlaying and fastening means toward the shoe to cause the release of the driver bar by movement of said member.
7. In a machine of the class described, the combination with means for pulling an upper over a last, of overlaying and fastening means, operating mechanism comprising a positive connection to said overlaying and fastening means to force said means inwardly toward the shoe, and means for breaking said positive connection at a definite point in the inward movement of said overlaying and fastening means, said operating mechanism including parts relatively movable when said connection is broken to actuate the fastening means.
8. In a machine of the class described, the combination with means for pulling an upper over a last, of overlaying and fastening means including a driver bar, operating mechanism comprising a positive connection to said overlaying and fastening means to force it inwardly toward the shoe, and means for substituting a yielding connection for said positive connection at a definite point in the inward movement of said overlaying and fastening means, said operating mechanism including a device for normally holding said driver bar against driving movement and operative when said positive connection is interrupted to release the driver bar.
9. In a machine of the class described, the combination with means for pulling an upper over a last, of overlaying and fastening means comprising a supporting arm mounted for movement toward and from the shoe and a driver bar mounted on said arm, an operating member having means for normally holding said driver bar against driving movement, a second arm mounted for movement toward and from the shoe and connected to said member, a positive connection between said arms through which movement is imparted from said member to the first named arm to carry said overlaying and fastening means inwardly toward the shoe, and means operative at a definite point in the inward movement of said arms to break said positive connection and permit said member to move relatively to the first arm for releasing the driver bar.
10. In a machine of the class described, the combination with means for pulling an upper over a last, of overlaying and fastening means comprising a supporting arm mounted for movement toward and from the shoe and a driver bar mounted on said arm, an operating member having means

- for normally holding said driver bar against driving movement, a second arm mounted for movement toward and from the shoe and connected to said member, a positive connection between said arms through which movement is imparted from said member to the first named arm to force said overlaying and fastening means inwardly toward the shoe, means operative at a definite point 10 in the inward movement of said arms to break said positive connection and permit said member to move relatively to the first arm for releasing the driver bar, and an additional yieldable connection between said 15 two arms arranged to operate when said positive connection is broken to hold the overlaying and fastening means in operative relation to the shoe.
11. In a machine of the class described, 20 the combination with means for pulling an upper over a last, of means movable inwardly toward the shoe for overlaying and fastening the margin of the upper, operating mechanism comprising a positive connection to said overlaying and fastening means to force it inwardly, means for substituting a yielding connection for said positive connection at a definite point in 25 the cycle of operations.
12. In a machine of the class described, 30 the combination with means for pulling an upper over a last, of overlaying and fastening means movable inwardly toward the shoe and operative in its inward movement to cause the upper pulling means to release 35 the upper, mechanism for moving said overlaying and fastening means toward the shoe including parts relatively movable to actuate the fastening means, a device for preventing the relative movement of said parts, and means arranged to act on said device substantially at the time when the upper is 40 released by the pulling means to cause the device to release said parts for relative movement.
13. In a machine of the class described, 45 the combination with means for pulling an upper over a last, of overlaying and fastening means movable inwardly toward the shoe and operative in its inward movement to cause the upper pulling means to release 50 the upper, mechanism for moving said overlaying and fastening means toward the shoe including parts arranged for relative movement in response to resistance encountered by said means in its movement toward the shoe to actuate the fastening means and a positive connection for normally preventing the relative movement of said parts, and means operative in the inward movement of 55 said overlaying and fastening means substantially at the time when the upper is released by the pulling means to break said positive connection and cause the actuation of the fastening means.
14. In a machine of the class described, 60 the combination with means for pulling an upper over a last, of means movable inwardly toward the shoe for overlaying and fastening the margin of the upper, and operating mechanism arranged to be positively connected to said overlaying and fastening means to force it inwardly and then 65 yieldingly connected to said means to hold it in operative position.
15. In a machine of the class described, 70 the combination with means for pulling an upper over a last, of means movable inwardly toward the shoe for overlaying and fastening the margin of the upper, operating mechanism comprising a positive connection to said overlaying and fastening means to force it inwardly, means for breaking said positive connection at a definite point in the inward movement of said overlaying and fastening means, and an additional device 75 for applying yielding pressure to the overlaying and fastening means to hold it in position when said connection is broken.
16. In a machine of the class described, 80 the combination with means for pulling an upper over a last, of means movable inwardly toward the shoe for overlaying and fastening the margin of the upper, operating mechanism comprising a positive connection to said overlaying and fastening means to force it inwardly, and means for substituting a yielding connection for said positive connection at a definite point in 85 the cycle of operations.
17. In a machine of the class described, 90 the combination with means for pulling an upper over a last, of means movable inwardly toward the shoe for overlaying and fastening the margin of the upper, operating mechanism comprising a toggle arranged to 95 be maintained substantially straight to impart inward movement positively to said overlaying and fastening means, means for breaking said toggle at a definite point in the cycle of operations, and a spring arranged 100 to act in place of said toggle to impart yielding pressure to said means when the toggle is broken.
18. In a machine of the class described, 105 the combination with means for pulling an upper over a last, of means movable inwardly toward the shoe for overlaying and fastening the margin of the upper, operating mechanism comprising a positive connection to said overlaying and fastening means to force it inwardly, means arranged to be operated by the inward movement of 110 said overlaying and fastening means to interrupt said positive connection, and spring means arranged to be substituted for said positive connection to apply yielding pressure to said means when the positive connection is broken.
19. In a machine of the class described, 115 the combination with shoe positioning means, of overlaying and fastening means, an arm mounted for movement inwardly toward the shoe and upon the outer end of which said overlaying and fastening means is supported, and operating mechanism connected to said arm at its outer end portion adjacent to said overlaying and fastening means for moving the arm inwardly toward 120 the shoe.
20. In a machine of the class described, 125 the combination with shoe positioning means, of overlaying and fastening means, an arm mounted for movement inwardly toward the shoe and upon the outer end of which said overlaying and fastening means is supported, and operating mechanism connected to said arm at its outer end portion adjacent to said overlaying and fastening means for moving the arm inwardly toward 130 the shoe.

- the combination with shoe positioning means, of overlaying and fastening means, an arm mounted for movement inwardly toward the shoe and upon the outer end of which said overlaying and fastening means is supported, a second arm also mounted for movement toward the shoe, means connected to said last named arm to move it inwardly, and a connection between said last named arm and the outer end portion of the first arm for imparting inward movement to said first arm.
20. In a machine of the class described, the combination with shoe positioning means, of upper fastening means comprising a supporting arm mounted for movement inwardly toward the shoe, a second arm also mounted for movement toward the shoe, means connected to said last named arm to move it inwardly, a positive connection between said two arms for imparting operative movement to the first arm, and means operative at a predetermined point in the inward movement of said arms to substitute a yielding connection for said positive connection.
21. In a machine of the class described, the combination with shoe positioning means, of upper fastening means comprising a supporting arm mounted for movement inwardly toward the shoe, a second arm also mounted for movement toward the shoe, means connected to said last named arm to move it inwardly, a toggle connection between said arms arranged to be held substantially straight for imparting movement positively to said first arm, means operative at a definite point in the inward movement of the arms to break said toggle, and a spring between said arms to apply yielding pressure to the first arm to hold it in operative position when the toggle is broken.
22. In a machine of the class described, the combination with shoe positioning means, of upper fastening means mounted for movement inwardly into operative relation to the shoe, operating mechanism comprising a positive connection to said fastening means to move it inwardly and a member movable relatively to the fastening means to actuate it when said positive connection is broken, and means for breaking said positive connection when the fastening means has been moved substantially into operative position.
23. In a machine of the class described, the combination with shoe positioning means, of upper fastening means mounted for movement inwardly into operative relation to the shoe, operating mechanism comprising a toggle arranged to be held substantially straight for imparting inward movement positively to said fastening means and a member movable relative to the fastening means to actuate it when said toggle is broken, means for breaking said toggle when the fastening means has been moved substantially into operative position, and yielding means for holding the fastening means in operative position after the toggle is broken.
24. In a machine of the class described, the combination with shoe positioning means, of upper fastening means mounted for movement inwardly into operative relation to the shoe and including a driver bar and a controlling member movable relatively to the driver bar to release it, a device for preventing relative movement between said member and the driver bar as the fastening means moves toward the shoe, and means arranged to act on said device at a definite point in the inward movement of the fastening means to render the device inoperative to prevent movement of said member relatively to the driver bar.
25. In a machine of the class described, the combination with shoe positioning means, of upper fastening means mounted for movement inwardly into operative relation to the shoe, mechanism for moving said fastening means inwardly including parts arranged for relative movement to cause the fastening operation to be performed, a device for normally preventing the relative movement of said parts, and means arranged to act on said device at a variably predetermined point in the inward movement of the fastening means to render the device inoperative to prevent relative movement of said parts.
26. In a machine of the class described, the combination with shoe positioning means, of upper fastening means movable inwardly into operative relation to the shoe, mechanism for operating said fastening means to fasten the upper, and a positively operating device for preventing the operation of said mechanism until the fastening means has arrived in a definite relation to the shoe.
27. In a machine of the class described, the combination with shoe positioning means, of upper fastening means movable inwardly into operative relation to the shoe, mechanism for operating said fastening means to fasten the upper, a device for normally preventing the operation of said mechanism, and means arranged to act on said device at a definite point in the inward movement of the fastening means to render it inoperative to prevent the operation of said mechanism.
28. In a machine of the class described, the combination with shoe positioning means, of upper fastening means comprising a supporting arm mounted for movement toward and from the shoe and a driver bar mounted on said arm, an operating member having means for normally holding said driver bar against driving movement, a connection between said member and arm for moving said arm toward the shoe, and means operative at a definite point in the inward movement of

said arm to break said connection and cause the release of the driver bar by the continued movement of said member.

29. In a machine of the class described, the combination with shoe positioning means, of means for overlaying and fastening the margin of the shoe upper, said overlaying and fastening means being movable toward the shoe into upper fastening position, and operating mechanism controlled by the shoe for moving said overlaying and fastening means positively to a position determined by the shoe irrespective of the resistance of the shoe materials.

15 30. In a machine of the class described, the combination with shoe positioning means, of means for overlaying and fastening the margin of the shoe upper, said overlaying and fastening means being movable toward the shoe into upper fastening position, positively operating mechanism for moving said overlaying and fastening means toward the shoe, and means controlled by the shoe for determining the position relatively to the shoe to which the overlaying and fastening means is moved by said positively operating mechanism.

31. In a machine of the class described, the combination with shoe positioning means, of means for overlaying and fastening the margin of the shoe upper, said overlaying and fastening means being movable toward the shoe into upper fastening position, operating mechanism for moving said overlaying and fastening means positively toward the shoe irrespective of the resistance of the shoe materials, and a member positioned by the shoe for determining in accordance with the size of the shoe the position to which said overlaying and fastening means is moved positively by said operating mechanism.

40 32. In a machine of the class described, the combination with shoe positioning means, of means for overlaying and fastening the margin of the shoe upper, said overlaying and fastening means being movable toward the shoe into upper fastening position, an operating member having a predetermined range of movement, a positive connection between said operating member and the overlaying and fastening means for moving said means toward the shoe, and a device controlled by the shoe for interrupting said positive connection at a point in the inward movement of the overlaying and fastening means determined by the size of the shoe.

60 33. In a machine of the class described, the combination with means for pulling an upper over a last, of devices for overlaying and fastening the margin of the upper at the opposite sides of the shoe, said devices being movable toward the shoe into upper fastening position, operating mechanism for moving said overlaying and fastening devices

positively toward the shoe, side clamps for engaging the opposite sides of the shoe, and members arranged to be positioned by said clamps in accordance with the width of the shoe for determining the positions to which the overlaying and fastening devices are moved positively by said operating mechanism.

20 34. In a machine of the class described, the combination with means for pulling an upper over a last, of devices for overlaying and fastening the margin of the upper at the opposite sides of the shoe, said devices being movable toward the shoe into upper fastening position, operating means positively connected to said overlaying and fastening devices to move them toward the shoe, side clamps for engaging the opposite sides of the shoe, and members arranged to be positioned by said clamps in accordance with the width of the shoe for interrupting the positive connections between said operating means and the overlaying and fastening devices when said devices have been moved to positions determined by the shoe.

25 35. In a machine of the class described, the combination with means for pulling an upper over a last, of side arms movable toward and from the opposite sides of the shoe and having overlaying and fastening devices thereon, an operating member, positive connections between said operating member and the side arms for moving said arms inwardly toward the shoe, and means controlled by the shoe for interrupting said positive connections when said arms have been moved to positions determined by the shoe.

30 36. In a machine of the class described, the combination with means for pulling an upper over a last, of side arms movable toward and from the opposite sides of the shoe and having overlaying and fastening devices thereon, an operating member, positive connections between said operating member and the side arms for moving said arms inwardly toward the shoe, side clamps for engaging the opposite sides of the shoe, and members arranged to be positioned by said clamps in accordance with the width of the shoe for interrupting said positive connections when the side arms have been moved to positions determined by the shoe.

35 37. In a machine of the class described, the combination with shoe positioning means, of means for overlaying and fastening the margin of the shoe upper, said overlaying and fastening means being movable toward the shoe into upper fastening position, an operating member, a positive connection between said operating member and the overlaying and fastening means for moving said means toward the shoe, and a device controlled by the shoe for substituting a yielding connec-

- tion for said positive connection when said overlaying and fastening means has been moved to a position determined by the shoe.
38. In a machine of the class described, the combination with shoe positioning means, of means for overlaying and fastening the margin of the shoe upper, said overlaying and fastening means being movable toward the shoe into upper fastening position, an operating member, a positive connection between said operating member and the overlaying and fastening means for moving said means toward the shoe, and mechanism controlled by the shoe for interrupting said positive connection at a point in the movement of said overlaying and fastening means determined by the shoe, said mechanism being adjustable to vary the time when said positive connection is thus interrupted.
39. In a machine of the class described, the combination with shoe positioning means, of means for overlaying and fastening the margin of the shoe upper, said overlaying and fastening means being movable toward the shoe into upper fastening position, and operating means for moving said overlaying and fastening means inwardly toward the shoe and for then actuating the fastening means to fasten the upper comprising mechanism controlled by the shoe for positively insuring a predetermined relation between the shoe and said overlaying and fastening means before the actuation of the fastening means takes place.
40. In a machine of the class described, the combination with shoe positioning means, of means for overlaying and fastening the margin of the shoe upper, said overlaying and fastening means being movable toward the shoe into upper fastening position, a member positively connected to said overlaying and fastening means to move said means toward the shoe and operative by continued movement to actuate the fastening means for fastening the upper, and a device controlled by the shoe for interrupting the positive connection between said member and the overlaying and fastening means at a point in the inward movement of said means determined by the shoe to release said operating member for continued movement to actuate the fastening means.
41. In a machine of the class described, the combination with shoe positioning means, of overlaying and fastening means including fastener driving means mounted for movement toward the shoe into upper fastening position, positively controlled means for locking said fastener driving means against driving movement as said overlaying and

fastening means moves toward the shoe, and a device positioned by the shoe for releasing said locking mechanism from positive control at a predetermined point in the inward movement of the overlaying and fastening means.

42. In a machine of the class described, the combination with means for pulling an upper over a last, of means for overlaying and fastening the margin of the upper, said overlaying and fastening means being movable inwardly to upper fastening position, operating mechanism for imparting inward movement to said overlaying and fastening means comprising a connection arranged to give way when said means has arrived at a predetermined position relatively to the shoe to cause the actuation of the fastening means in response to continued movement of said mechanism, and supplemental yielding means arranged to act automatically to hold said overlaying and fastening means from outward return movement during such continued movement of the operating mechanism.

43. In a machine of the class described, the combination with means for pulling an upper over a last, of an arm mounted to swing inwardly toward the shoe and having overlaying means and fastener driving means thereon, mechanism for swinging said arm toward the shoe, said mechanism being operative by continued movement after the arm has arrived in predetermined relation to the shoe to release the fastener driving means, and a supplemental device automatically operative to hold said arm yieldingly against outward return movement as the fastener driving means is thus released.

44. In a machine of the class described, the combination with means for pulling an upper over a last, of an arm mounted to swing inwardly toward the shoe and having overlaying means and fastener driving means thereon, operating mechanism for swinging said arm toward the shoe, said mechanism being operative by continued movement after the arm has arrived in predetermined relation to the shoe to release the fastener driving means, and a spring directed inwardly against the outer face of said arm and arranged to be subjected to stress by the continued movement of said operating mechanism to hold the arm against outward return movement when the fastener driving means is thus released.

In testimony whereof I have signed my name to this specification.

ERIC A. HOLMGREN.
